SEWING MACHINE NEEDLE GUARD

Maxwell B. Sklar, Brooklyn, N. Y.

Application June 4, 1936, Serial No. 83,433

2 Claims. (Cl. 112—261)

One object of this invention is the provision of an improvement in sewing machines, more particularly a guard for the needle of the machine to prevent accidental contact of the fingers of an operator with the descending needle. The guard also serves other purposes, among which may be mentioned that it prevents the cloth being operated upon, especially linings, from turning over on top of the presser bar foot and thus getting caught in the foot.

Another object of the invention is the provision of such a guard having its front portion hingedly mounted on the extremity of the presser bar foot, so that it may be readily rotated into position where free access to the needle may be had for the purpose of threading the needle and other purposes.

A still further object is the provision of means for releasably locking the forward section of the guard in either upright or extended position.

The above and other objects will become apparent in the description below, in which characters of reference refer to like-named parts in the accompanying drawing.

Referring briefly to the drawing, Figure 1 is a side view of a portion of a sewing machine, illustrating the application of the guard thereto.

Figure 2 is a front view of Figure 1.

Figure 3 is a rear view of Figure 1.

Figure 4 is a cross-sectional view taken on the line 4—4 of Figure 3, with a fragment of cloth shown in the machine.

Figure 5 is a side elevational view of a modified form of guide, and the presser bar foot on which it is mounted.

Figure 6 is a cross-sectional view of the modified form, taken on the line 6—6 of Figure 7.

Figure 7 is a cross-sectional view taken on the line 7—7 of Figure 6.

Referring in detail to the drawing, the numeral 10 indicates the lower end of the sewing machine head from which the presser bar 11 descends, and also the needle bar 12 in which the needle 13 is secured. The presser bar 11 is provided with a yoke 14 at its lower end in which the slotted upper end 15 of the foot 16 is adjustably mounted by means of a thumb screw 17. The foot 16 comprises the upright arm 18 and the horizontal forked base 19, the slotted-upper end 15 being joined to the upright arm 18 by the web 20. The base 19 is provided with a short prong 21 and a long prong 22 separated by a slot 23. The guard 24 comprises a unitary member of thin or sheet metal having a side wall 25 secured along its edge 26 to the arm 18 and along its lower edge

27 to the base 19. The guard 24 is secured to these members of the foot 16 by soldering, welding, or in any other desired manner. The side wall 25 is provided with a right-angled extension wall 28, integral therewith. This front wall 28 is provided at its end with an arcuate tongue 29. A substantially oval opening 30 is cut out of the front wall 28 and extends through a portion of the arcuate tongue 29. A vertical line 31 is drawn at the base of the oval opening 30 directly in line with the needle 13, when viewed from the front. This line is provided by painting, etching, or in any other desirable manner, and serves to indicate to the operator the position of the lower tip of the needle 13, since the latter descends below the base of the opening 30. The cloth 32 lies below the base 19 of the foot 16. When the operator guides the cloth through the machine, his fingers approach close to the foot 16, and the guard 24 shields his fingers from accidental contact with the descending needle in a manner which is obvious.

In the modified form shown in Figures 5, 6, and 7, the presser bar foot 16 is the same as that shown in the previously described figures. The guard 33 is formed of two sections 34 and 35. The section 34 is secured to the arm 18 and the base 19 in the same manner as the entire guard 24 is secured in the previously described figures. The section 35 is provided with a side wall 36 having its lower edge 37 formed of the same contour as the upper edge 38 of the section 34 so that they complement each other when the section 35 is in raised or upright position, as shown in Figure 6, and thus form a continuous side wall 35 for the guard. The base 19 is similarly provided with a short prong 21 and a long prong 22. The latter, however, has on its ends a pair of ears 39 in which a pin or shaft 40 is rigidly held. The section 35 of the guard 33 has its side wall 36 provided with a front extension wall 41 substantially similar to the front wall 28 of the guard 24. The front wall 41 is also provided with a substantially oval opening 30 and an upper arcuate tongue 29. The lower extremity of the front wall 21 is rolled loosely about the pin 40 in the form of a sleeve 42. The upper surface of the sleeve 42 (Figure 6) is flattened to provide a flat edge 43, and at right angles thereto a similarly flattened surface 47 is provided. A spring 44 is secured at its rear end 45 to the top of the base 19 by soldering, welding, or in any other desirable manner, near the side walls of the guard. Its outer end 46 extends over the sleeve 42. When the guard section 35 is in upright position 55

with its side wall closed, the tip 46 of the spring 44 lies flush against the flat edge 43 of the sleeves 42 and thus serves to releasably lock the section 35 in upright position. To rotate the latter into the position shown in broken lines in Figure 6, the tongue 29 is pushed forward and when the section 35 is swung outward through an arc of approximately 90 degrees, the flat surface 47 of the sleeve 42 will lie flat under the spring end 46 and thus the guard section 35 will be releasably locked in its extended or open position. In the latter position, the guard permits complete observation of the lower end of the needle 13 and also permits ready threading of the needle from the side through the space previously occupied by the side wall 36 of the section 35.

Obviously, modifications in form and structure may be made without departing from the spirit and scope of the invention.

20 I claim:

1. In combination with a sewing machine presser bar foot having a vertical arm and a base at right angles to said arm, a wall secured to the sides of said arm and base, a member comprising a side wall and a front wall at right angles thereto having its front wall hingedly secured on the outer extremity of said base, said front wall being adapted to be rotated into substantially vertical position, said side walls coming into contact with each other when said wall is in vertical position to provide a closed side wall formed of said two side walls, said front wall when rotated outwardly from said vertical position removing its side wall from contact with said first named wall

and giving access to the upper surface of said base from said side, said front wall having a cut out opening therein, and means for releasably locking said front wall in either of said two positions.

2. In combination with a sewing machine presser bar foot having a vertical arm and a base at right angles to said arm, a wall secured to the sides of said arm and base, a member comprising a side wall and a front wall at right angles thereto having its front wall hingedly secured on the outer extremity of said base, said front wall being adapted to be rotated into substantially vertical position, said side walls coming into contact with each other when said wall is in vertical position to provide a closed side wall formed of said two side walls, said front wall when rotated outwardly from said vertical position removing its side wall from contact with said first-named wall and giving access to the upper surface of said base, said front wall having an opening therein, means for locking said front wall in either of said two positions, said means comprising a pin on the end of said base, a sleeve on the lower end of said front wall surrounding said pin, said sleeve having a pair of flat surfaces substantially at right angles to each other, a spring finger secured at one end of said base and having its other end projecting over said sleeve, said other end of said spring lying flush against one of said flat edges when said front wall is in upright position and against the other of said flat edges when the front wall is in extended position.

MAXWELL B. SKLAR.
